BRASSIÈRE

Jack J. Lo Cascio, Bayonne, N. J., assignor to
Even-Pul Foundations, Inc., New York, N. Y.,
a corporation of New York

Application May 11, 1953, Serial No. 24,939

Term of patent 14 years

(Cl. D20—4)

To all whom it may concern:

Be it known that I, Jack J. Lo Cascio, a citizen of the United States of America, residing at Bayonne, in the county of Hudson and State of New Jersey, have invented a new, original, and ornamental Design for a Brassière, of which the following is a specification, reference being had to the accompanying drawing forming a part hereof:

Figure 1 is a front perspective view of a brassière, showing my new design;

Figure 2 is a fragmentary front elevational view thereof, on an enlarged scale.

The dominant features of my design reside in the portions shown by full lines. The back of the brassière is conventionally plain.

I claim:

The ornamental design for a brassière, as shown and described.

JACK J. LO CASCIO.
